UNITED STATES PATENT OFFICE.

ARTHUR H. SWEETLAND, OF LONG BEACH, CALIFORNIA.

DESIGN FOR AN ELECTRICALLY-OPERATED HAND-DRILL.

58,117.

Specification for Design.

Patented June 7, 1921.

Application filed June 1, 1920. Serial No. 385,838. Term of patent 14 years.

To all whom it may concern:

Be it known that I, ARTHUR H. SWEETLAND, a citizen of the United States, residing at Long Beach, in the county of Los Angeles, State of California, have invented a new, original, and ornamental Design for an Electrically-Operated Hand-Drill, of which the following is a specification, reference being had to the accompanying drawing, forming part thereof.

The figure is a perspective view of an electrically operated hand drill, showing my new design.

I claim:

The ornamental design for an electrically operated hand drill, as shown.

ARTHUR H. SWEETLAND.
